UNITED STATES PATENT OFFICE.

HIRAM T. BUSH, OF DETROIT, MICHIGAN.

DESIGN FOR A LATCH-HANDLE.

SPECIFICATION forming part of Design No. 33,947, dated January 22, 1901.

Application filed December 26, 1900. Serial No. 41,167. Term of patent 7 years.

To all whom it may concern:

Be it known that I, HIRAM T. BUSH, a citizen of the United States, residing at Detroit, in the county of Wayne and State of Michigan, have invented and produced a certain new and original Design for a Latch-Handle, of which the following is a specification, reference being had therein to the accompanying drawings, in which—

10 Figure 1 is a front elevation. Fig. 2 is a plan, and Fig. 3 is an end elevation.

A is an oblong substantially rectangular base-plate having rounded edges and corners and a central boss B, which rounds into 15 the plane of the plate. C is a flattened loop or ring arranged in a plane perpendicular to the base and centrally of said boss in the direction of the shorter dimension of said plate.

The inner side of said loop merges into a circular plate D, concentric and adjacent to said boss. At one end of the loop is a crooked finger E, extending toward the plane of the plate and then outward.

The leading features of the design are the plate, the loop arranged in a plane perpendicular to said plate, and the crooked finger extending from one end of said loop.

What I claim as my invention is—

The design for a latch-handle, substantially as herein shown and described.

In testimony whereof I affix my signature in presence of two witnesses.

HIRAM T. BUSH.
